UNITED STATES PATENT OFFICE.

FRANK M. THOMAS, OF PIGGOTT, ARKANSAS, ASSIGNOR OF ONE-HALF TO LOUIS LINKE, OF PARAGOULD, ARKANSAS.

AIR-LINE COUPLING.

1,402,978.

Specification of Letters Patent. Patented Jan. 10, 1922.

Application filed September 20, 1919. Serial No. 325,092.

To all whom it may concern:

Be it known that I, FRANK M. THOMAS, a citizen of the United States, residing at Piggott, in the county of Clay and State of 5 Arkansas, have invented certain new and useful Improvements in Air-Line Couplings, of which the following is a specification.

The invention relates to means for coupling the air pipe of railway cars by means 10 of which the brakes are controlled, the purpose being to provide a coupler which is susceptible of being easily and cheaply repaired and maintained in working condition and which will prevent the escape or waste 15 of air pressure and which is automatic in action, both in coupling and uncoupling, and which will adapt itself to the various movements of the cars without any tendency to strain the parts or to open the joint.

20 The drawings illustrate a preferred embodiment of the invention. However, it is to be understood that in adapting the same to meet different conditions, various changes in the form, proportion, and minor details 25 of construction may be resorted to without departing from the nature of the invention as claimed hereinafter.

Referring to the drawings hereto attached;

30 Fig. 1 is a view in elevation of part of a railway car provided with an air pipe coupling embodying the invention,

Fig. 2 is a vertical longitudinal section of 35 a portion of the coupler showing the parts on a larger scale,

Fig. 3 is a transverse section on the line 3-3 of Fig. 2 looking to the front, as indicated by the arrow,

Fig. 4 is a vertical longitudinal section of 40 the forward portion of the coupler,

Fig. 5 is a top view of the forward portion of the coupler partly in section,

Fig. 6 is a top view of two coupler members in coupled position, parts being broken 45 away to show more clearly the relation of the parts when in cooperative position to admit of the air passing from the air pipe of one car to the air pipe of the next car.

Fig. 7 is a sectional detail of the joint 50 formed between the sections at the outer end of the air pipe,

Fig. 8 is a top view of the outer ends of complementary coupler members in engagement.

55 Corresponding and like parts are referred

to in the following description and indicated in the several views of the drawings by like reference characters.

The numeral 1 designates a fragment of a car body and 2 part of a supporting truck 60 therefor. The numeral 3 designates a coupling of any desired type, whereby the cars are coupled when in train. Cross beams 4 support the car body on the frame work of the truck in a manner well understood. The 65 parts herein referred to may be of any usual construction and are illustrated to demonstrate the application of the present invention which relates more particularly to the air pipe or train-line coupler and parts intimately associated therewith. A hanger 5 is 70 pendent from the forward cross beam or bolster 4 and constitutes a support for the air pipe coupler. A frame 6 is disposed within the hanger 5 and is pivotally connected thereto by vertically disposed gudgeons 7 which preferably form a part of the frame 6. Ribs 8 project inwardly from the top and bottom of the frame 6 and are centrally disposed. The ribs 8 flare rearwardly, 75 as indicated at 9 and their forward faces curve, as shown most clearly in Fig. 2. As shown most clearly in Fig. 3, the frame 6 is transversely elongated and is provided in end portions of its top and bottom with vertically aligned openings to receive vertical pins 10.

A hollow abutment 11 is mounted in the frame 6 and is closed at its rear end and open at its front end which latter is enlarged to form a head 12 which engages the ribs 8 whereby the rearward movement of the abutment 11 is limited. The head 12 tapers forwardly and its rear is made rounding to engage the forward rounded faces of 95 the ribs 8, whereby the abutment 11 is adapted to have a limited rocking movement in a vertical plane. It is also observed that the abutment 11 is adapted to have a pivotal movement horizontally with the frame 6 100 about the gudgeons 7. Lugs 13 project laterally from the abutment 11 in opposite directions and are apertured to receive the vertical pins 10. Fig. 3. Expansible helical springs 14 are mounted upon end portions of the pins 10 and are confined between the lugs 13 and the top and bottom portions of the frame 6. In this manner, the abutment 11 is yieldably held in a given position. The coupler comprises a body 15 which is 110

mounted in the abutment 11 and normally 5 pressed forward by means of an expansible helical spring 16 located within the abutment 11 and interposed between the rear ends of the body 15 and abutment. The body 15 is enlarged at its outer or forward end and provided with opposed extensions 17 and 18. The extensions 17 and 18 flare forwardly and constitute guides to give 10 proper direction to cooperating coupler members when adjacent cars are run together. The body 15 is hollow and formed with a longitudinal opening 19 in which is fitted a member 20 which is retained in place 15 by suitable fastenings 21 which are threaded into the sides of the body 15. The opening 19 is contracted at its forward end and the member 20 is similarly reduced, as shown most clearly in Fig. 4. The member 20 is 20 insertible and removable relatively to the body 15 through the rear end of the opening 19. A longitudinal passage 22 is formed in the rear portion of the member 20 and communicates at its outer end with the air 25 pipe line, as indicated at 23 and at its inner end with a longitudinal opening or passage 24 formed in the forward portion of the member 20. A member 25 is slidably mounted in the opening 24 and is tubular and is 30 normally pressed forward by means of an expansible helical spring 26 mounted upon the forward portion of the member 25 and confined between a shoulder at the outer end thereof and an inner shoulder of the 35 member 20. The member 25 is provided at its outer end with a head 27 in which is formed a lateral opening in communication with the opening formed longitudinally in the member 25. A gasket or packing 28 is 40 fitted on a side of the head 27 in line with the lateral opening and insures a tight joint between the members 25 when the coupler of one car is engaged with the coupler of the next car. A stop 29 projects laterally from 45 the head 27 in the rear of the lateral opening and is adapted to engage the end of the companion member 25 and limit the movement of the two members 25 when the coupler of one car is in engagement with the 50 coupler of the next car coupled thereto. The opening of the member 25 is adapted to register or make connection at its inner or rear end with the passage 22 when the member 25 is pressed rearwardly. The longitudinal 55 opening of the member 25 extends laterally through said member, as indicated at 30 in Fig. 4. When the member 25 is pressed forwardly by the spring 26, the opening 30 is moved away from the opening 60 or passage 22 and the latter is closed by the part of the member 25 in the rear of the opening 30. However, when the member 25 is pressed rearwardly as is the case when companion coupler members are in 65 engagement, the opening 30 is in register with the opening or passage 22, so that the air may have unobstructed passage through the opening of the members 20 and 25 and from the air pipe of one car to the air pipe of the next car coupled thereto. By having 70 the inner faces of the extensions 17 and 18 inclined, the outer ends of the coupler members are caused to come together in proper relation when adjacent cars are coupled. The heads 27 of the members 25 are likewise subjected to lateral pressure to bring the gaskets or packing in close relation to maintain a close joint between companion members 25. A band 31 is mounted upon the coupler body 15 and is yieldably connected to the inner or rear cross member 4 by means of rods 32 which have their contiguous ends slidably connected and pressed apart by an expansible helical spring 33. Stops 34 projecting laterally from the body 80 15 are adapted to engage the band 31 and limit the forward movement of the coupler. The air pipe or train line 23 is provided at its outer or forward end with a plurality of elbow sections, indicated most clearly in 90 Fig. 1. These sections have a ball and socket connection, as indicated at 35 in Fig. 7. Rings or like elements 36 constitute connecting means for securing the sections at the ball and socket joints. The rings or connecting elements 36 are made secure by bolts or like fastenings 37. A gasket or packing 38 is interposed between one of the connecting elements and the section engaged thereby to maintain a close joint. The elbow sections and the ball and socket joints enable the successful use of an all metal air pipe and provide for the various movements to 95 obviate binding. It is to be understood that each end of a 105 car is equipped alike with a coupler constructed substantially as herein disclosed. When two cars are run together in the act of coupling, the members comprising the air pipe coupler likewise are brought into coupling engagement and each member is pressed rearwardly against the tension of the spring 16 and as the air pipe coupling members come together, the heads 27 are pressed together laterally, thereby insuring the formation of a close joint. When the members 25 are pressed rearward, the openings therein are caused to connect with the 110 passages 22 by the lateral openings 30 moving to a position to register with the lateral openings at the forward ends of the 115 passages 22. By having the train or air pipe coupler mounted as disclosed herein, it will adapt itself readily to the various movements of the cars. As shown most clearly in Fig. 3, the frame 6 is adapted to oscillate about a vertical axis and the hollow abutment 11 is adapted to oscillate about a longitudinal axis. The body 15 of the coupler is of square form and the opening in 120 125 130

the abutment 11 is of corresponding shape to admit of the coupler and abutment 11 oscillating together. It is to be understood that the forward portion of the coupler is 5 yieldably supported so as to allow for vertical adjustment. This is indicated most clearly in Fig. 1, which shows a hanger 39 through which the body 15 of the coupler passes, said body resting upon a plate yield- 10 ably supported by means of a spring 40. The hanger 39 is of such formation as to admit of the various movements of the coupler, whereby it may adapt itself to the cars without causing any binding action. 15 The foregoing description and the drawings have reference to what may be considered the preferred, or approved form of my invention. It is to be understood that I may make such changes in construction and 20 arrangement and combination of parts, materials, dimensions, et cetera, as may prove expedient and fall within the scope of the appended claims.

Having thus fully described my invention, what I claim as new and desire to secure by Letters Patent is:—

1. In a train pipe coupler, a supporting frame, a hollow abutment mounted for rocking movement in a vertical plane and 30 movable horizontally with the frame and provided at its sides with lateral lugs, pins passing through said lugs and supported in the upper and lower portions of the frame, expansible helical springs mounted upon 35 end portions of the pins between the lugs and portions of the frame in which the pins are mounted and a coupler slidably mounted in the abutment.

2. In a train pipe coupler, a supporting 40 frame having inwardly extending ribs medially of its top and bottom, a hollow abutment mounted in the frame and having a head engaging the said ribs and provided at its sides with lugs, vertical pins passing 45 loosely through the lugs and supported in the top and bottom portions of the frame, expansible helical springs mounted upon end 50 portions of the pins and exerting a pressure on the lugs of the abutment and a coupler slidably mounted in the hollow abutment.

3. In a train pipe coupler, a supporting frame having rib portions formed thereon, a hollow abutment mounted in the frame and having a head engaging said ribs, said abut- 55 ment provided with lugs formed upon the sides thereof, and yieldable means engaging said lugs for normally holding said abutment in proper alinement, and a coupler slidably mounted in the hollow abutment.

4. In a train pipe coupler, a supporting frame, means for pivotally mounting said supporting frame upon a support for lateral swinging movement, a hollow abutment mounted within said frame and anchored against movement upon said frame in one 65 direction, a coupler slidably mounted within said hollow abutment, means for yieldably engaging the inner end of said coupler for constituting a yieldable buffer therefore, flanges carried by the sides of said abutment, and yieldable means engaging said flanges for permitting said abutment to rock within said frame and be normally and yieldably held in a horizontal position. 70

5. In an air pipe coupler for railway cars, 75 a member provided with a longitudinally extending passage, a complementary member slidably mounted within the first mentioned member and provided with a longitudinally extending opening, said slidably mounted 80 member provided with an outlet port adapted to be brought into registration with said passage when moved inwardly with respect to said passage, means for locking said first mentioned member within a coupler, spring 85 means engaging said slidably mounted member for normally urging the same outwardly with respect to the coupler, a head formed upon the outer end of said slidably mounted member, said head provided with a laterally 90 extending lip adapted to constitute an abutment against which a cooperating slidably mounted member upon an adjoining coupler abuts for the purpose of producing an efficient interlocking engagement between a 95 pair of couplers.

6. In an air pipe coupler for railway cars, a member having a longitudinally extending passage formed therein, a complementary member slidably mounted within the first 100 mentioned member, yieldable means constituting a buffer for said complementary member, a head carried by said complementary member said head provided with a laterally 105 extending flange and having a communicating port at each end, the communicating port at one end being adapted to communicate with said longitudinally extending passage, said flange constituting means for limiting the sliding movement of said complementary 110 member in one direction, and also constituting an abutment for producing correct alinement of the communicating opening formed in the respective complementary members carried by cooperating couplers. 115

In testimony whereof I affix by signature.

FRANK M. THOMAS.
